PULP BEATING AND WASHING ENGINE

Melvin A. Mills, Lawrence, Mass., assignor to
Elizabeth M. O'Neil, Watertown, N. Y.Application February 11, 1930, Serial No. 427,579
Renewed February 6, 1934

4 Claims. (Cl. 92—24)

This invention relates in general to paper making machinery and in particular to pulp beating engines, and has for its general object to provide a pulp beating engine embodying an improved combination and arrangement of features designed to reduce the amount of time required to thoroughly disintegrate or shred a given amount of pulp stock, and to reduce the amount of power required to effect the disintegrating or shredding 10 operation.

The invention has special reference to improvements in pulp beating engines of the type embodying a tub and means therein, in the form of a plurality of beater rolls, operating successively, 15 to disintegrate or shred the pulp and to cause a circulation of the pulp within the tub, whereby all of the pulp is caused to be subjected to the action of the disintegrating means, and in this connection it is an important object of the invention to provide, in association with each beater roll, means to substantially eliminate clogging or back pressure of the pulp mass thereagainst. Also, in this connection, it is an object of the 20 invention to so arrange said rolls relative to one another that clearing of the pulp mass from certain of the rolls is materially assisted by other of the rolls, thereby to provide, as heretofore stated, for rapid and thorough disintegration of the pulp by the utilization of a relatively small amount 25 of power.

The invention also has in view to provide for utilizing the advantages of gravity to assist in circulating the pulp stock within the tub, and 30 contemplates the employment of a succession of beater rolls designed to be driven at different rates of speed and to operate successively to more finely disintegrate the pulp, whereby reduction of a given mass of pulp stock to a desired disintegrated condition may be accomplished in a single 35 operation of a single machine.

With the foregoing and other purposes in view, the invention consists in the novel features of construction, combination and arrangement of parts as will be hereinafter more fully described, illustrated in the accompanying drawing and defined 40 in the appended claims.

In the drawing, wherein like characters of reference denote corresponding parts in the different views:—

50 Figure 1 is a top plan view of a pulp beating engine embodying the novel features of the present invention; and

Figure 2 is a longitudinal sectional view therethrough.

55 Referring to the drawing in detail, 10 designates

a pulp tub of elongated form within which is a central upstanding longitudinally extending feather or partition 11 which terminates short of the ends of the tub and thereby divides the tub into a single endless trough or passage 12 which 60 extends contiguous to the sides and ends of the tub and consists essentially of the legs *a*, *a*, respectively, through which the pulp mass is adapted to travel in opposite directions.

In accordance with the invention the bottom 65 of the tub 10 preferably is inclined at a suitable angle relative to the horizontal so that the major portion of the pulp mass in seeking its level tends to flow from the highest end of the trough 12 and to collect in the lowest end thereof.

Within one of the legs *a* of the trough 12, is arranged a plurality of beater rolls 13 of known or of any suitable construction, each mounted on a horizontal, transverse shaft 14 journaled for rotation in suitable bearings 15. Said rolls are 70 located at suitably spaced intervals longitudinally of the tub and, respectively, at different elevations, the lowest roll being located nearest to the lowest end of the tub and the highest roll nearest to the highest end of the tub, the intermediate 75 roll or rolls, as the case may be, preferably being disposed at an elevation higher than the lowest roll and lower than the highest roll.

In the present instance three beater rolls 13 are employed, the lowest roll preferably being of 80 considerably larger diameter than the other rolls and the latter rolls being either of the same diameter or of different diameters as may be desired.

Disposed within the leg *a* of the passage 12 within which are arranged the beater rolls 13 is 85 a dam or stop structure designated generally as 16 over which the pulp stock must pass in its travel through said leg of said passage. Carried by this dam or stop structure are knife devices 17 with which the knives of the beater rolls cooperate to 90 disintegrate the pulp, there being, as shown, a knife device 17 individual to each beater roll.

Formed in the dam or stop structure 16 below each beater roll 13 is an arcuate depression 18, each of which, in conjunction with its related 100 beater roll, provides a relatively narrow channel 19 for the passage of the pulp material beneath the roll.

At the approach side of the lowest roll 13 the dam or stop structure 16 is inclined upwardly, as 105 indicated at 20, from the bottom of the tub 10 to the depression 18 below said roll, to facilitate feeding of the pulp mass into the first channel 19.

The topmost part of the inclined portion or 110

apron 20 preferably is disposed slightly above the bottom of the first depression 18 substantially as shown, while at the opposite or delivery side of the first roll 13 the surface of the depression 18 extends considerably above the topmost portion of the apron 20 and is merged, by a rounded surface 21, directed generally towards the intermediate roll 13, with a surface 22 the topmost portion of which is disposed in a horizontal plane passing 10 preferably and approximately through the axis of the first roll 13.

From its topmost portion the surface 22 curves downwardly and towards the intermediate roll 13 and extends to and joins the surface of the related arcuate depression 18 at the approach side of said roll preferably in a plane considerably below the axis of said roll. On the other hand, at the delivery side of the intermediate roll, the surface of the related arcuate depression 18 is 15 merged, by a rounded surface 23 directed generally towards the last or highest roll, with a surface 24, the topmost portion of which is disposed considerably above the lowermost portion of the surface 23 preferably in a horizontal plane disposed substantially at or a little below the elevation 20 of the axis of said intermediate roll.

From its topmost portion, the surface 24 curves downwardly and towards the last or highest roll 13 and extends to and joins the surface of the 30 arcuate depression 18 related to the highest roll at the approach side of said roll and in a plane preferably considerably below the axis of said roll. On the other hand, the surface of the arcuate depression 18 beneath said last roll extends, 35 at the delivery side of said roll, considerably above the lowermost portion of the surface 24 to a peak 25 from which an inclined surface 26 slopes downwardly to the bottom of the tub 10.

Above the beater rolls 13 is arranged a hood 40 28 for cooperation with said rolls, and with the dam or stop structure previously described, to facilitate circulation of the pulp stock through the passage 12. This hood includes, above each roll, an arcuate portion 29 more or less closely approaching its related roll at the delivery side thereof and, at the opposite side thereof, merging into a lip 30 directed downwardly and inwardly towards the roll and terminating substantially in the medial horizontal plane thereof. From the 45 lip 30 associated with the last or highest roll 13 an arched portion 31 of the hood 28 extends to and is joined with the arcuate portion 29 associated with the intermediate roll, and from the lip 30 associated with the intermediate roll, a similar 50 55 arched portion 32 of said hood extends to and is joined with the arcuate portion 29 associated with the first or lowest roll 13. In addition, an arched portion 33 of the hood preferably extends from the arcuate portion 29 associated with the last or highest roll 13 into overlying relation to a portion 60 of the downwardly sloping surface 26.

The beater rolls are adapted to be rotated in the direction indicated by the arrows in Fig. 2 of the drawing whereby the pulp stock will be caused to circulate through the trough or passage 12 in the direction indicated by the arrows in Fig. 1 of the drawing. Thus, with the rolls in motion and a quantity of pulp stock contained in the tub 10, it is manifest that the pulp will be 65 70 75 carried by and with the first beater roll through the first channel 19 and be thrown by centrifugal force over the topmost portion of the surface 22 and against the arched hood surface 32 from whence it will fall onto said surface 22 and be directed by the latter towards the intermediate

roll 13. Some of the pulp stock may, of course, adhere to the first beater roll and be carried by the latter past the forward end of the arcuate hood portion 29 above said roll. Such stock, if it is thrown off against said arcuate hood portion, will be directed by the lip 30 of said hood portion towards the roll, and because of its gravity imparted momentum will readily be picked up by the roll and again directed through the channel 19 where, of course, it will be a second time subjected to the disintegrating action of the roll blades and the fixed blades 17.

By reason of the surface 22 sloping downwardly towards the intermediate roll 13 it is manifest that as the pulp stock passes over the highest part of said surface it will be directed by gravity towards the intermediate roll and be prevented from flowing back into the first channel 19. Thus, the first channel 19 will be maintained practically free of any excess accumulation of pulp stock and the first roll will encounter minimum resistance to rotation, substantially the only power required for rotation of said roll being that necessary to elevate the relatively small mass of pulp contained in the related channel 19.

The dam and hood formations at the intermediate and the highest rolls being in substance the same as the corresponding formations at the first roll, the foregoing operation is repeated at said intermediate and highest rolls, each roll thus being maintained practically free of any back pressure of the pulp mass and thereby being substantially freely rotatable as is manifest.

The rolls 13 may be individually driven or one of them may be either directly or indirectly driven and the others may be driven therefrom. For example, as illustrated in Fig. 1, the first or lowest roll is directly driven by a motor 34 and the respective rolls are connected together by pulleys 35 and belts 36, whereby each roll is driven from said motor, the pulleys 35 preferably being of the cone type whereby the speed of the rolls may conveniently be varied relative to one another. In this connection, to further assist in maintaining the rolls free of back pressure of the pulp mass, each successive roll preferably is rotated at a slightly greater rate of speed than the roll behind and next adjacent thereto, as regards the direction of circulation of the pulp mass, whereby the tendency of the intermediate and the highest 115 120 125 rolls is to cause the pulp stock to pass through the channels 19 related to these rolls faster than pulp is supplied to said channels so that the intermediate roll assists in maintaining the channel of the lowest roll free of any excess accumulation of pulp, and the highest roll accomplishes the same purpose with respect to the intermediate roll.

Obviously, if desired, the first or lowest roll 13 may be simply a paddling or pulp circulating roll and all disintegration of the pulp may be accomplished by means of the other rolls. Preferably, however, each roll is a beater roll and each successive roll is of a construction to more finely disintegrate the pulp stock than the roll therebehind, which, combined with the relatively high 135 140 145 speed of the last roll and its consequent brushing as well as disintegrating action on the pulp, eliminates the necessity of the pulp being treated in a second or so-called "refining" machine, the pulp, after it has been thoroughly beaten by means of the present engine, resembling very closely the so-called and well known "Jordaned" stock.

While in the title and the foregoing description the present machine has been referred to as a "Pulp beating engine", the same obviously is 150

capable of use as a washing engine for pulp, rags or the like either in the form shown or by placing ordinary cylinder washers in the leg *a* of the trough 12 opposite to the leg in which the beater 5 rolls are located. Moreover, while the legs *a*, *a* of the trough 12 are shown in this instance disposed in side to side relation, it is manifest that, if desired, these legs may be disposed one above the other with the beater rolls located in the upper 10 leg, in which event the dam or stop structure 16 may serve as a horizontal partition or so-called "midfeather" to separate the respective legs of the trough. Furthermore, by making the first roll 13 of sufficiently large diameter, the other 15 rolls obviously may be disposed either entirely or in major part at least below the center of the first roll instead of above the center of said roll as herein shown.

Without further description it is thought that 20 the features and advantages of the invention will be readily apparent to those skilled in the art, and it will of course be understood that changes in the form, proportion and minor details of construction may be resorted to, without departing 25 from the spirit of the invention and scope of the appended claims.

I claim:

1. A pulp beating engine comprising a pulp tub having a circulating trough, a pair of spaced beater 30 rolls disposed in said trough for successively beating and circulating the pulp, a dam member between the rolls, a hood over said rolls inclusive of an arcuate portion disposed above each roll, and an arched portion connecting the adjacent 35 ends of said arcuate portions, said arched portion at its end adjacent to the receiving side of the roll last acting on the pulp being disposed closer to said dam member than the end of said

arched portion which is disposed adjacent to the delivery side of the roll first acting on the pulp.

2. A pulp beating engine comprising a pulp tub having a trough, a pair of spaced beater rolls disposed in said trough for successively beating the pulp and circulating it through said trough, a dam member between the rolls, and a hood over the rolls inclusive of an arched portion overlying the space between the rolls and cooperating with said dam member to provide a throat extending from the delivery side of the roll first acting on the pulp to the receiving side of the roll last acting on the pulp and of progressively decreasing sectional area from said first mentioned roll to said second mentioned roll. 80

3. A pulp beating engine comprising a pulp tub having a trough, a pair of spaced beater rolls disposed in said trough for successively beating the pulp and circulating it through said trough, a dam member between the rolls, and a hood over the rolls inclusive of a substantially arcuate portion overlying each roll and an arched portion extending between the rolls and connecting said arcuate portions, each arcuate portion at the receiving side of its related roll being deflected inwardly toward said roll. 95

4. A pulp beating engine comprising a pulp tub having a trough, a pair of spaced beater rolls disposed in said trough for successively beating the pulp and circulating it through said trough, a dam member between the rolls, and a hood over the rolls inclusive of a substantially arcuate portion overlying each roll and an arched portion extending between the rolls and connecting said arcuate portions, each arcuate portion at both the receiving and delivery sides of its related roll being deflected inwardly toward said roll. 100
